James Wheeler

United States Patent Office.

JAMES WHEELER, OF DOWAGIAC, MICHIGAN.

Letters Patent No. 95,175, dated September 21, 1869.

IMPROVEMENT IN POTATO-DIGGERS.

The Schedule referred to in these Letters Patent and making part of the same.

To all whom it may concern:

Be it known that I, JAMES WHEELER, of Dowagiac, in the county of Cass, and State of Michigan, have invented a new and useful Machine for Digging Potatoes; and I do hereby declare that the following is a full, clear, and exact description of the construction and operation of the same, reference being had to the annexed drawings, making a part of this specification, in which—

Figure 1 is a top view, and

Figures 2 and 3 are detached sections.

The nature of my invention consists in constructing a potato-digger, of that class which is used without carrying-wheels or beam, the team being hitched similar to the manner of hitching to a common road-scaper.

To enable others skilled in the art to make and use my invention, I will proceed to describe its construction and operation.

In the accompanying drawings—

A represents a broad iron hoop, open on the under side.

The part of the hoop above the line of its horizontal diameter forms a semicircle, to which are attached the handles B B and draught-bail C.

The open ends and lower part of said hoop are curved backward from the vertical line of the upper part, and form shares, with their cutting-edges turned inward, as seen at D D, and gradually approach each other as they extend backward, the rear ends of which nearly meet, leaving an opening of not more than two inches.

The outer edge of each share is provided with holes, in which the iron rods 1 2 3 4 5 6 7 8 9 10 are fastened, to form a screen.

The rear ends of said rods are supported by the shaft E, and sufficiently elevated to come a little above the surface of the ground.

This screen is agitated by a rocking motion, produced by the cam-wheels on the ends of shaft E.

Said cams are so arranged that when the longest radius or diameter of one is in a vertical position, the longest diameter of the other will be in a horizontal position, holding one end of shaft E higher than the other, but as the cams roll forward, the high end is thrown down, and the other end thrown up, causing a rocking motion of the rear end of said screen, for the purpose of separating the potatoes from the dirt.

The circle of the hoop A should be made sufficiently large to embrace the entire breadth of the potato-hill.

It will be seen that the space of earth left undisturbed by the rear ends of shares D D will prevent the mass of earth and potatoes from drawing forward as the shares D D are drawing under the outer edges of the potato-hill; and the rods of which the screen is composed should be sufficiently close as to gather all the potatoes of consequence.

H H represent braces, extending from the hoop A to the handles B B, for the support of the handles.

In this invention the bow or hoop A forms the main body of the machine, with shares D D in one piece, combining great simplicity with strength and durability, and its mode of operation is too obvious to need further description.

Having thus fully described my invention,

What I claim as new, and desire to secure by Letters Patent, is—

1. The construction of the bow or hoop A, with its shares D D in one piece, as and for the purposes set forth.

2. In combination with the hoop A and shares D D, the screen, composed of the rods 1 2 3 4 5 6 7 8 9 10, (or any suitable number,) the shaft E, cam-wheels a a, handles B B, braces H H, and bail C, when constructed, arranged, and combined as set forth.

JAMES WHEELER.
